UNITED STATES PATENT OFFICE.

LADURA ALEXANDER BROWN, OF UNIONTOWN, PENNSYLVANIA.

AUTOMATIC CUT-OVER AND SAFETY SWITCH.

Application filed March 16, 1927. Serial No. 175,823.

This invention relates to automatic cut-over and safety switches for use in controlling two sources of electric current to a single motor, and while not limited thereto, relates more particularly to switches of this class particularly designed for use on mine locomotives and similar machines which have a trailing cable and trolley for connecting with the source of supply.

10 The object of this switch is to automatically cut-over or transfer from one source of current supply to the other and to prevent the cutting-over of one source while the other source is in use.

15 At the present time a hand-operated switch is generally in use to cut-over from one source of current supply to the other on mine locomotives, and such switches are often operated intentionally and accidentally by the operator with a load on the motor, which causes considerable arc at the switch contacts. This arcing many times seriously burns the operator or causes him to jump from the locomotive which also many times

20 results in serious injury.

The present switch is completely enclosed in a flame-proof box as a protection against any arc accidentally formed, and is electrically interlocked so that the switch can not operate until the current is removed from the main contacts.

25 In the drawings—

Figure 1 is a side elevation of a switch constructed in accordance with this invention, with the cover plate removed for clearness.

Figure 2 is an end elevation with the casting omitted for clearness.

Figure 3 is a diagram of the circuits made by the switch of Figures 1 and 2.

Referring more particularly to the drawings, the numeral 2 designates the casing of the switch as a whole, which may be composed of metal or other fire resisting material and entirely encloses the switch. An insulating back-board 3 is secured to the back of the casing 2 and supports the switch parts. A pair of brackets 4 and 4' are secured to the back-board 3 and serve to support an insulating base 5 and coils 6 and 7.

A U-shaped bracket support 8 is secured to the base 5, and a switch arm 9 is pivotally

mounted between the sides of the bracket 8 by a pin 10. A pair of contact members 12 and 13 are mounted one at each end of the arm 9, and are adapted to engage stationary input contacts 14 and 15, respectively, secured at the opposite ends of the base 5.

The contacts 12 and 13 are held in position by a bolt 16 and spring 17, which spring is mounted on the bolt 16 between the upper face of the contacts and a nut 18 threaded on the bolt. The springs 17 serve to tension or press the contacts 12 and 13 against the stationary contacts 14 and 15 when the coil 6 is energized.

The coils 6 and 7 are provided with hollow or tubular cores of insulating material 19 and 19', respectively, which extend upwardly through the brackets 4 and 4'. Iron plunger members 20 and 21 are connected to the arm 9 on opposite sides of its pivotal mounting by link members 22 and 23, respectively, and are mounted within the tubular core members 19 and 19' of the coils so as to be attracted by the coils 6 and 7 when said coils are energized.

Energization of coil 6 will attract the plunger 20 and cause the switch arm 9 to rock about its pivot and engage the contact member 12 with the input contact 14, while energization of the coil 7 will attract the plunger 21 and cause the switch arm 9 to rock about its pivot in the reverse direction and engage the contact member 13 with the input contact 15.

The contacts 12 and 13 are connected by a flexible conductor 24, which in turn is connected to a single output terminal 25.

A pair of switch arms 26 and 26' are pivotally mounted on a pin 27 below the coils 6 and 7 and carry bridge contacts 28 and 29, respectively, at their free ends adapted to bridge contacts 30-31 and 32-33, respectively, when the respective arms are rocked toward the coils. The arms 26 and 26' are provided with small tubular core plungers 34 and 35, respectively, which project upwardly within the cores 19 and 19' of the coils 6 and 7 and are adapted to be attracted by said coils when said coils are energized and thus rock said switch arms.

A V-shaped bearing block 36 is mounted on the lower side of the switch arm 9 and is adapted to be engaged by a spring-pressed

ball 37 mounted in a bushing 38. The ball 37 bears against the inclined faces of the block 36 and serves to yieldably hold the arm 9 in either extreme position; since said ball must be depressed by said block in order to permit the arm 9 to rock to the other position.

Due to the light weight of the core plungers 34 and 35 and the switch arms 26 and 26', coupled with the holding resistance of the ball 37 on the switch arm 9, when the coils 6 and 7 are energized the plungers 34 and 35 will be the first to move into the coils and, therefore, the bridge pieces 28 and 29 will bridge the contacts 30-31 and 32-33 prior to the movement of the switch arm 9.

Extension rods 39 and 40 are secured to the lower ends of the plungers 20 and 21, respectively, and extend downwardly through the plungers 34 and 35. The lower ends of the rods 39 and 40 are threaded to receive nuts 41 and 42, respectively, and bridge plates 43 and 44 are slidably mounted on the rods 39 and 40, respectively, above the nuts 41 and 42 and are normally held against the nuts by coiled springs 45 and 46. The springs 45 and 46 are mounted around the rods 39 and 40 and have their lower ends bearing against the plates 43 and 44 while their upper ends bear against pins 47 and 48.

The bridge plates 43 and 44 are adapted to engage and bridge contacts 49-50 and 51-52, respectively, when the plungers 20 and 21, respectively, are attracted by their coils.

Now referring to Figure 3 of the drawings, the electrical connections and control features of the switch will be described. A₁ designates the trolley pole source of supply which is connected to the input contact 14, and B₁ designates the trailing cable or extension source of supply which is connected to the input contact 15. C₁ designates a controller, and M₁ designates the motor to be operated.

A power line 55 leads from the output terminal 25 to the controller C, and a power line 56 leads from the controller to one side of the motor M, while the other side of the motor is grounded through a line 57. The one end of the winding of coil 6 is connected by a line 58 to the input contact 14, while the other end is connected to contacts 52 and 33 by a line 59.

One end of the winding of the coil 7 is connected to input contact 15 by a line 60, while the other end is connected to contacts 49 and 30 by a line 61.

Contacts 31 and 50 are connected in series by a line 62 and contacts 51 and 32 are connected in series by a line 63. Contacts 50 and 51 are connected in series with an interlock switch 64 in the controller C by a line 65. The switch 64 closes the circuit to

ground and is adapted to be closed only when the controller is in off position breaking the power circuit to the motor D.

With the switch in the position shown in the diagram of Figure 3, current will flow from the trolley pole A through contacts 14 and 12 and connector 24 to output terminal 25, thence through line 55 to the controller C and from the controller through line 56 to motor M and thence through line 57 to ground, thus completing the motor circuit.

Now assuming that it is desired to operate the locomotive or other apparatus operated by the motor M from the trailing cable B and assuming that the trolley pole A has been removed from the trolley wire and that the trailing cable B has been placed on the trolley wire. With the elements in this position, current will flow from the trolley wire through the cable B, to the contact 15, then through line 60 and coil 7 to line 61, and contact 49, across the bridge piece 43 to contact 50, thence through line 65 and controller interlock 64 to ground, thus completing a circuit through the coil 7, causing the coil 7 to attract the plungers 21 and 35. Plunger 35 will be the first attracted due to its weight and the mechanical holding mechanism on the arm 9 retarding the movement of the plunger 21. The attraction of plunger 35 will operate the switch arm 26' and cause the plate 29 to bridge contacts 32 and 33. However, since the trolley pole A is removed from the trolley line, no circuit will be completed by the operation of the switch arm 26.

The attraction of the plunger 21 will rock the switch arm 9 so as to engage contacts 13 and 15, completing a power circuit from the cable B through the contacts 13 and 15 and flexible connector 24 to output terminal 25, thence through line 55 to controller C, line 56 to motor M and line 57 to ground.

It will, of course, be understood that when the switch arm 9 is rocked by the attraction of the plunger 21, contacts 12 and 14 will be separated, and plunger 20 will be raised so as to remove the bridge piece 43 from contacts 49 and 50, and that the ball 37 will engage the opposite face of the block 36 so as to mechanically hold the switch arm 9 in position.

When the plunger 21 is attracted, the bridge piece 44 will be lowered to bridge across the contacts 51 and 52.

Now assuming that the cable B is removed from the trolley wire and it is desired to operate the motor from the trolley pole A again, the trolley pole A is placed on the trolley line so that current will flow through the pole A to the input contact 14, then through line 58 to coil 6, and line 59 to contact 52, then through the bridge piece 44 to contact 51 and line 65 to controller interlock 64, and through the interlock 64 to

ground, thus energizing the coil 6. Energization of the coil 6 will attract the plungers 20 and 34. Plunger 34 will be the first to be attracted due to its small weight and the mechanical holding mechanism on the arm 9 retarding the movement of the plunger 20. The attraction of the plunger 35 will operate the switch arm 26 and cause the plate 28 to bridge contacts 30 and 31. However, since the cable B is removed from the trolley line, no circuit will be completed.

The attraction of the plunger 20 will rock the switch arm 9 so as to engage contacts 12 and 14, completing a power circuit from the trolley A through the contacts 12 and 14 and flexible connector 24 to the output terminal 25, thence through line 55 to the controller C, line 56 to the motor M and line 57 to ground. The operation of the switch arm 9 to close the contacts 12 and 14 will, of course, disengage the contacts 13 and 15. If it is attempted to cut over to the cable B while the trolley pole A is still engaged with the trolley line, as soon as the cable B is engaged with the trolley line, current will flow from the trolley line through the cable B to contact 15 and then through line 60, coil 7, and line 61 to contact 49, thence across the bridge piece 43 to contact 50, then through line 65 and controller interlock 64 to ground, thus completing a circuit through the coil 7 to attract the plungers 21 and 35. Due to the light weight of the plunger 35 and the resistance of the mechanical holding mechanism on the switch arm 9, the plunger 35 will be the first to be attracted and, therefore, switch arm 26 will be rocked to move the bridge plate 29 across the contacts 32 and 33. Immediately upon the bridging of contacts 32 and 33 a circuit will be completed from the trolley pole A to contact 14, then through the line 58, coil 6, and line 59 to contact 33, then through the bridge plate 29 to contact 32, and wire 63 to contact 51, and from the contact 51 through the line 65 and interlock 64 to ground, thus energizing the coil 6. Energizing the coil 6 will cause the coil 6 to attract the plunger 20 and, since the coils 6 and 7 and plungers 20 and 21 are balanced, the attraction of plunger 20 will balance the attraction of plunger 21 by the coil 7, and the switch arm 9 will remain stationary until the trolley pole A is removed, at which time the switch will operate to complete the circuits described above when the cable B is used instead of the trolley pole A.

Now assuming that an attempt is made to cut over to the trolley pole A while the cable B is engaged with the trolley line, as soon as the trolley pole A is engaged with the trolley wire, current will flow through the pole A to the contact 14 and then through line 58, coil 6, and line 59 to contact 52,

thence across the bridge piece 44 to contact 51, then through line 65 and controller interlock 64 to ground, thus completing the circuit through the coil 6, and causing the coil 6 to attract the plungers 20 and 34. Due to the light weight of the plunger 34 and the resistance of the mechanical holding mechanism on the switch arm 9, the plunger 34 will be the first to be attracted and, therefore, switch arm 26 will be rocked to move the bridge plate 28 across the contacts 30 and 31. Immediately upon the bridging of contacts 30 and 31 a circuit will be completed from the cable B to contact 15, then through the line 60, coil 7, and line 61 to contact 30, then through the bridge plate 28 to contact 31 and wire 62 to contact 50, and from the contact 50 through the line 65 and interlock 64 to ground, thus energizing the coil 7. Energization of the coil 7 will cause the coil to attract the plunger 21, and since the coils 6 and 7 and plungers 20 and 21 are balanced as heretofore described, the attraction of plunger 21 will balance the attraction of the plunger 20 by the coil 6 and the switch arm 9 will remain stationary until the cable B is removed, at which time the switch will operate to transfer from one source of current to the other.

If, when an attempt is made to transfer or cut over from one source of current supply to the other in any of the above described instances, while the controller C is in "on" position, the interlock 64 will be open and none of the above described control circuits can be completed, thereby positively preventing the cutting over from one source of supply to the other while a load is on the motor M, that is until the controller C is in "off" position.

I claim—

1. A cut-over switch having two input contacts, a single rocking switch element movable into circuit closing relation with one or the other of said contacts, means for yieldably holding said switch element in circuit closing position, and operating means for said switch element including a pair of plungers and magnetic operating coils for said plungers, a control switch for controlling the energizing circuit to each of said coils, and operating means connecting each of said switches with the plunger operated by the coil controlled by the other switch, whereby the attraction of either of said plungers by the coil associated therewith will operate to close the control switch to the other coil.

2. A cut-over switch having two input contacts, a single rocking switch element movable into circuit closing relation with one or the other of said contacts, mechanical means for yieldably holding said switch element in circuit closing position, and operating means for said switch element includ-

ing a pair of plungers and magnetic operating coils for said plungers, a control switch for controlling the energizing circuit to each of said coils, and operating means 5 connecting each of said switches with the plunger operated by the coil controlled by the other switch, whereby the attraction of either of said plungers by the coil associated therewith will operate to close the control 10 switch to the other coil.

3. A cut-over switch having two input contacts, a switch element movable into circuit closing relation with either of said contacts, mechanical means for yieldably holding said switch element in circuit closing position, an electro-magnetic coil having one end of its winding connected to one of said input contacts, a second electro-magnetic coil having one end of its winding connected 15 to the other input contact, each of said coils having the other ends of their windings connected to the ground through switches, plungers connected to said switch element and said last named switches and operatively associated with said coils so as to be attracted by said coils when said coils are energized and adapted when attracted to operate said switch element and said last named switches, said last named switches being adapted to be moved into circuit closing 20 position to close the circuit to the deenergized coil upon the attraction of said plungers, a second switch element operable by said coils, said last named element having 25 plungers adapted to be more readily attracted than said first named plungers, said last named switch element being adapted to be attracted by either of the coils immediately upon

on energization of said coils and to move into position to close the circuit through the 40 deenergized coil prior to the operation of said switches operable by said first named plungers, whereby unless the input contact connected to said deenergized coil is deenergized, said last named coil will immediately become energized and its attraction force coupled with said mechanical holding means for said first named switch element will maintain said first named switch element stationary. 50

4. The combination with a motor, a controller therefor, and two sources of current supply to said controller, of a cut-over switch having two input contacts, a switch element movable into circuit closing relation with either of said contacts, means for yieldably holding said switch element in circuit closing position, and operating means for said switch element including a pair of plungers connected to said switch element and magnetic operating coils for said plungers, control switches for controlling the energizing circuit to each of said coils, operating means connecting each of said switches to the plunger operated by the coil controlled by the other switch, whereby the attraction of either of said plungers by the coil associated therewith will operate to close the control switch to the other coil, and means associated with said controller for preventing the energization of either of said coils until said controller is in off position. 60
